UNITED STATES PATENT OFFICE.

STEPHEN V. JOYCE, OF NEW YORK, N. Y.

CHUTE FOR PROPORTIONING AND FORWARDING MATERIALS.

1,313,852.

Specification of Letters Patent.

Patented Aug. 19, 1919.

Application filed May 28, 1918. Serial No. 237,116.

To all whom it may concern:

Be it known that I, STEPHEN V. JOYCE, a citizen of the United States, residing in the borough of Manhattan, city, county, and State of New York, have invented certain new and useful Improvements in Chutes for Proportioning and Forwarding Materials, of which the following is a specification, reference being had to the accompanying drawings and the characters of reference marked thereon.

My invention relates to improvements in chutes adapted to be used for forwarding materials, such as ashes, lime, sand, broken stone, cement, gravel and similar materials, and the structures for that purpose may be built sufficiently large and strong to forward materials of that character; but the device may also be modified, decreased in size, and otherwise adapted to be utilized in other industries and arts, without departing from the spirit of my invention, which contemplates a series of slideways, tubes or runs, each of which can be adapted to receive a predetermined quantity from a suitable supply, with means to adjust the flow into each, in such relative proportions as may be desired, and simultaneously and conjointly to cut off and to discharge such flow from all, such cut off devices consisting of sliding, hinged, or pivoted gates, and likewise to reset the parts to continue the operation.

An example of my invention is illustrated in the accompanying drawings, in which Figure 1 is a view of one such slideway, partly in section; Fig. 2 is a plan of two such slideways joined to each other; Fig. 3 is a sectional view on the line 3—3 of Fig. 2; Fig. 4 is a sectional view on the line 4—4 of Fig. 2; Fig. 5 shows a modification of the sliding gates to be attached for opening and closing the slideway, and Fig. 6 is a section of Fig. 5 on the line 6—6; Fig. 7 is a plan showing the chute in position disposed so as to receive the materials separately at the upper end, and to carry the proportioned materials to the discharge end.

A is the chute, in this example of my invention, composed of two slideways B and C. The slideway B may be composed of exterior side piece 1, and interior sidepiece 2, and a floor 3, when the slideways are made separately and bolted together as shown in Fig. 3; but the middle portion may be made of one solid piece as shown in Fig. 4; 4 is a support for the bearing of the shaft 5, which shaft supports a working beam or bar 6, to which it is secured by collars 7, 7; the interior end of the shaft 5 is provided with a suitable clutch 8, rotating in a support 9, secured to the side piece 2; the clutch 9 is adapted to receive a key 10. At one end of the bar 6 a gate 11 is provided pivotally attached thereto and to the other end of said bar 6 a gate 12 is also pivotally attached, each gate being attached by bolts and nuts 13, 13, which may be provided with washers 14, 14 as shown plainly in Fig. 3.

The gates 11, 12, are provided with guide pieces 15, 15, adapted to be adjusted to and securely held in place on the side pieces 1, 2, by bolts or pins 16, 16 as also clearly shown in Fig. 3, and these guides 15, 15 may be secured at desired positions in the chutes on the sides of the slideways, through suitable holes 17, 17, provided therein, as clearly shown in Fig. 2. The interior end of the shaft 5 is provided with a clutch 9, corresponding to the clutch 9, and adapted to be locked thereto by the key 10, for operating both working beams simultaneously; the exterior end of the shaft 5 in slideway C, rotates in a support 4, and terminates in a squared or hexagonal portion, adapted to take on the handle 18; such angular portion terminating in a reduced threaded part adapted to receive a nut 19, which is adapted to secure the handle in place.

On the side of the slideway C a support 20, clearly shown in Fig. 1 is provided, in which holes 21, 21, are made, which correspond to holes in the handle 18, through which pins or bolts may be inserted to hold the handle in any desired position when it is

desired to fix it in place. The gates 11, 12, are so adjusted to the beams 6, 6, that when one of said gates is down and resting against the floor of the slideway, the other of such 5 gates will be elevated, leaving the slideway at that part open.

The chute is to be placed in position at a suitable angle as shown in Figs. 1 and 7, the upper part resting against an elevated 10 place, such as a ceiling or other part, from which the material is to be discharged into the chute, and such place is so arranged by a suitable partition or division 40, that the material entering one of the slideways will 15 be separate from the material entering the other slideway, until it reaches the discharging end of both. At the discharging ends of the slideways a suitable hopper 22, is provided, to receive the materials as they 20 are discharged and lead them to a suitable mixing or other machine provided for their reception.

Inasmuch as the flow of the materials may 25 be unequal, that is the material passing down one slideway may move more rapidly than that passing down the other, an additional gate 23, is provided, which has a rod 23^a, connecting it pivotally to a handle 25, which handle 25 is pivotally supported on 30 an upright 26, and extends across the chute, so that by means thereof, the gate 23, may be raised and lowered as desired, to regulate the quantity of material allowed to pass 35 into the slideway. The handle 25, where it impinges against the upright 27 is provided with holes and the upright 27 is provided with corresponding holes, and through these by means of a suitable pin or bolt, the gate 23, may be held at any suitable elevation. 40 The slideway C is provided with a similar gate 24, having a rod 24^a pivotally connecting it to a handle 28, which is pivoted to the crosspiece 29, and is also provided with holes corresponding to holes on the other 45 side of the upright 27, and by means of such handle 28, the gate 24, may be raised and lowered, and held in any desired position by pins or bolts inserted in the arm 28, and the holes in the upright 27.

50 The method of operation is as follows: The chute A is taken to the place where it is intended to be used, and set up and supported at the desired angle, the upper end adjusted to an opening in the floor or level 55 above it, and a division or partition as 40, provided, by means of which the material to be forwarded and measured through one slideway will be kept separated from another, until the quantity in each slideway has 60 been properly measured. The lower end of the chute is placed at a convenient point to lead the materials into a hopper 22, connected with a mixing or other receptacle. The attendant will first note whether the 65 capacity between the gates 11, 12, in each

slideway is properly adjusted, that is, if the mixture of the material is to be of equal parts, that the gates 11 and 12, are of equal distance apart in each slideway, or he will adjust the gates in each as may be desired, 70 for instance, adjusting one slideway to take in, say a yard, and the other to take in one-half, or other proportion of a yard, between the gates 11, 12. He will then raise the gates 23, 24, and allow the desired quantity to run into each slideway turning the handle 18 to raise the upper or receiving gates 12, 12. He will then note whether the material in both slideways is moving at the same pace, and if it is he will commence 80 operations, but if he finds that the material in one slideway is moving more rapidly than required, he will adjust the gates 23, 24, at such elevation as will allow the desired flow, pinning the same in position on the upright 85 27 by means of the handles 25, 28, by which the gates are held in position to allow the flow of material into each slideway at the proper speed.

As it may sometimes happen that the flow 90 of the materials or some of them is so rapid in one or both of the slideways as to overflow the lower end of the same, covers 95 30, 30, are provided, which are to be laid across the top edges of the slideways and held in place by rods 31, 31, passing through hasps 32, 32. Of course it will be understood that if desired the entire slideways from end to end may be provided with such covers as 30, 30, laid across the top with 100 recesses cut in them for adjustment to the portions projecting from the sides of the slideways, so that open, or partly open, or entirely closed slideways may be employed.

In Figs. 1 and 2 the two slideways shown 105 are of equal width and depth, and the gates 11, 12, shown in the drawings are of equal distances apart in both slideways, and for some purposes that arrangement may produce the desired results. But in case it is 110 desired to send a smaller quantity through one slideway than through the other, and the proportions cannot conveniently be reached by means of regulating the position of the gates on the bars 6, 6, another 115 means of decreasing the quantity of material passing through one of the slideways is provided, which consists of a suitable extra strip or piece 34, which may be secured by means of bolts and nuts 35, to one side of one of the 120 slideways to narrow the same, and decrease its capacity.

As it may be desired at times to pass material through the slideways which cannot be retarded very well by the spadelike 125 motion of the gates 12, 12, such for instance as broken stone, I show a modification of the cut off devices by substituting for the sliding gates 11, 12, hinged or pivoted gates 36, 36, Figs. 5 and 6, which 130

gates 36 are pivoted at one end 37, 37, to the sides of the slideways, and terminate in bail-like arms 38; also adapted to be attached to working beam 6, as clearly shown 5 in Figs. 5 and 6; the operation being, that when pivoted gates 36 are lying upon the floor of the slideway the material is allowed to pass over them and impinge against the pivoted gate 36 which is elevated; and when 10 that is lowered, the flow at the other end of the beam 6, is cut off by raising the pivoted gate.

While I have shown in these drawings and by the description of my invention, an 15 arrangement of a chute consisting of two slideways, it will be obvious that several slideways may be prepared and bolted together, and the outer end of the shaft 5, suitably extended, and provided with bearing supports, and attachments to added 20 working beams, similar to 6, 6, as may be desired. When only one such additional slideway is to be added, the shaft 5 would terminate, as shown in Fig. 2, resting upon 25 the outer edge of the added slideway; but if two slideways should be added the arrangement shown for the clutches could be repeated upon the continued shaft 5, so that slideways three, or four, etc., could be used 30 together or separately with two slideways as shown in Fig. 2. Gates similar to the gates 23, 24, with their pivoted handles and stopping devices could of course be provided 35 also by suitable uprights and a cross beam, without departing from the spirit of my invention.

Having thus described my invention, what I claim as new and desire to secure by Letters Patent, is:—

40 1. The combination with a chute, alternately opening and closing charge measuring gates mounted within the chute at a predetermined distance apart, and a gate arranged above the charge measuring gates 45 to regulate the flow of material thereto.

2. The combination with a chute formed with separate slideways, a pair of alternately opening and closing charge measuring gates mounted in each slideway a predetermined distance apart, independent operating means for each pair of gates, and a clutch connection between the two independent operating means.

3. The combination with a chute formed 55 with separate slideways, a pair of alternately opening and closing charge measuring gates mounted in each slideway a predetermined distance apart, means for simultaneously operating the charge measuring gates of the different slideways, and an independent gate mounted in each slideway above the charge measuring gates to regulate the flow of material to the latter.

4. The combination of a chute formed 65 with separate slideways, a pair of charge

measuring gates mounted in each slideway a predetermined distance apart, a shaft operatively connected to each set of charge measuring gates for alternately opening and closing the same, and a clutch connection 70 between the shafts for simultaneously operating all of the charge measuring gates.

5. The combination with a chute, of a pair of spaced gates pivotally connected to the bottom of the chute and foldable against 75 the same when in an open position, and a working beam having the ends thereof operatively connected to the swinging ends of the gates for alternately opening and closing the same.

80 6. The combination with a chute formed with separate slideways which receive material from separate sources of supply and discharge simultaneously into a common receptacle, adjustable charge measuring 85 gates within each of the slideways, and a gate arranged above the charge measuring gates to regulate the flow of material thereto, the charge measuring gates enabling the material received from the different sources 90 to be discharged into the common receptacle in predetermined proportions.

7. The combination with a chute formed 95 with separate slideways, a pair of alternately opening and closing charge measuring gates mounted in each slideway a predetermined distance apart, a working beam operatively connected to each pair of gates, shafts journaled upon the slideways and carrying the working beams, and a clutch 100 connection between the shafts.

8. The combination with a chute formed 105 with separate slideways which receive material from independent sources of supply and discharge into a common receptacle, a pair of charge measuring gates mounted in each slideway a predetermined distance apart, working beams operatively connected at their ends to the charge measuring gates for alternately opening and closing the same, 110 and means for locking the working beams together to obtain a simultaneous operation of the gates.

9. The combination with a chute, spaced 115 charge measuring gates mounted within the chute and pivotally connected to the bottom of the chute so as to be foldable against the same, a transverse shaft extending across the chute, a working beam carried by the transverse shaft, and link means between the ends of the working beam and the swinging ends of the respective charge measuring gates.

10. The combination with a chute formed 125 with separate slideways which receive material from independent sources of supply and discharge into a common receptacle, a pair of alternately opening and closing charge measuring gates mounted in each slideway, the gates of each pair being ad- 130

justable toward and away from each other to regulate the sizes of the respective charges, and a clutch connection between the two sets of gates whereby they may be 5 independently or simultaneously operated.

11. The combination with a chute, of a pair of spaced gates pivotally connected

to the bottom of the chute and foldable against the same when in open position, and means having a link connection with the 10 swinging ends of the gates for alternately opening and closing the same.

STEPHEN V. JOYCE.
